UNITED STATES PATENT OFFICE

GÜNTHER MEYER-JAGENBERG, OF DUSSELDORF, GERMANY.

MANUFACTURING PAPER BOXES AND THE LIKE.

Application filed April 16, 1927, Serial No. 184,334, and in Germany August 3, 1926.

This invention has reference to a machine for the manufacture of boxes, such as card board boxes and the like and provided with a neck, in which the neck strip of material 5 is inserted into the main card board pattern which in this operation places itself with its side portions around the neck strip. In accordance with this invention the winding plunger or the like for the production 10 of the neck strip is made in two sections, and the wound up neck strip is pushed from the point of winding onto an axially displaceable section of the plunger or the like, by means of which it is then forced into a 15 tube or the like together with the main card board pattern body, while at the same time the manufacture of a new neck strip is going on by winding upon the retained or lagging section of the plunger. By proceeding in this manner the manufacture of 20 the boxes is greatly accelerated, and this acceleration of the operation is further assisted by a movable guiding instrumentality for the neck strip which is fed to the winding plunger or the like and which by such 25 guiding means is forced against the winding plunger immediately upon the release of the same. Controlling means regulating the taking off of the patterns of card board from a supply provide for a proper 30 and correct timing of the feeding of the cardboard patterns notwithstanding the great distance of the supply from the point of treatment of the boxes, while the feeding 35 of a neck strip is prevented in the case of the failing to feed of a main cardboard pattern by means of a feeler or the like.

Upon the accompanying drawing the invention is illustrated by way of exemplification in Fig. 1 in side view with partial 40 longitudinal section; and in Fig. 2 in front view of the machine. Fig. 3 is a plan view of part of the machine. In Figs. 4 to 6, the machine is shown in the same longitudinal 45 section as represented in Fig. 1, but with a different relative operating position of the working parts. Fig. 7 illustrates a neck strip and a main card board body before assembling the same, and Fig. 8 shows 50 the finished box.

A strip of card board or similar material 1 is drawn off from a supply roller, not shown, by means of a tappet, pusher arm or the like 2, 3 and by means of a rocking 55 lever 4 operatively connected thereto, and it

is then passed to a gluing device 58 by which it is provided on its underside with a strip-like coating of adhesive material. The operation of the lever 4 is effected by a bar 59 which is drawn against a cam disc 60 on the driven shaft 63 by means of a spring 60 acting on roller 61. The neck strip 1 which is provided with glue or the like is fed by means of guide bars 5 disposed laterally of the glued strip to a cutting device 6 and to a rockingly disposed guide channel 7 by means of which the neck strip is moved to the winding mandrel, plunger or the like 8. The guide channel 7 is rockingly reciprocated in the direction 70 of the winding mandrel 8 by means of a pinion 9 and rack bar 10 operatively connected to a cam disc 11 on the driven shaft 63. The rack bar 10 is connected to the under-knife of the cutting device 6 and is 75 adapted to vertically reciprocate same, while the upper knife is stationary. At its extremity a hollow shaft 47 carries the winding mandrel 8 which is exchangeably connected thereto, the said shaft 47 being 80 rotatably journalled in a support 12 and being adapted to be rotated intermittently at certain timed periods by means of a gear wheel 48 which is temporarily engaged by a partially toothed wheel 50 mounted on the 85 driving shaft 49. Adjustable supporting springs 13 mounted on a frame 14 are longitudinally displaceable over the winding mandrel 8 and a plunger head 15. The frame 14 is preferably suspended from a 90 bar 51 adapted to be reciprocated and to be guided in the frame 12, 12^a. The movement of the bar 51 with the frame 14 and the supporting springs 13 is effected from a cam disc 52 disposed upon the shaft 49 95 and with the groove 53 of which the roller 56 of a lever 55 is adapted to engage which is rockingly disposed on the stud 54. The slotted end of the lever 55 is engaged by a tappet 57 on the bar 51. The supporting 100 springs 13 upon their displacement slide with their lugs 16 (Fig. 3) in the grooves 17 of the winding mandrel 8. The grooves 17 extend also along the part 46 and on this member there are provided running or 105 contacting surfaces which are adapted to be employed for different sizes of plungers. The plunger head 15 is exchangeably secured to an axially movable rod 18 which is disposed in the interior of the hollow 110

shaft 17 of the winding mandrel and projects therefrom. The axial displacement of the bar or rod 18 is effected by a lever 65 rockingly disposed on the stud 64 and being 5 engaged by means of a roller 66 with a groove 67 of the cam disc 52. A clamping device 19 disposed on the winding mandrel between the lower pair of springs 13 serves for the purpose of retaining the wound up 10 neck strip at the connecting joint and a compression spring 20 is provided adapted to force the pressure jaw 21 against the winding head 8, while the said jaw is subsequently lifted off by a cam 44 operated 15 by a cam disc 68 on the shaft 49. A tube or the like 22 adapted to snugly surround the finished boxes carries at its end confronting the plunger spring-acting side walls 23 which are inwardly projected. A 20 bracket or supporting arm 24 is projected with its supporting surface 25 between the guide bars 26 of a guiding frame 27 in front of said tube 22 in such a manner that the supporting surface 25 is adapted to 25 catch and become engaged with a main card board pattern 45 delivered from a supply 29 in the usual manner by means of a slide, not shown, and a pair of feeding rollers 28. The supporting arm 24 serves merely 30 for the quicker and more reliable feeding of the card board pattern in front of the opening of the tube or the like 22, and the said arm is controlled from the cam disc 68 by means of a bar 69. A feeler 30 which is 35 preferably loaded and is engaged between the rollers 28 is rotatably disposed with its shaft 31 in front of the container for the supply of card board patterns in such a manner that, upon the lowering of a piece 40 of card board 45, the feeler by means of a system of levers 42, 43 acts upon a bar 32. With its free end this bar is engaged in a wedge-like fashion between the guide 33 of the tappet carriage 3 and a guide 34 which 45 is moved transversely with relation to the guide 33 by means of springs 35. A tongue or tappet 36 having suitable guiding means is moved in the guide 34 and cooperates with an angular stop 37 secured to the tappet 2 in such a manner that it does not become engaged with the angular stop upon the operation of the feeler 30, so that the tappet 2 will be operated and the strip of card board may be fed forward. If, however, 50 the feeler 30 is not actuated, that is to say, in case no card board pattern 45 is lowered, the tongue or tappet 36 moves below the angular stop 37 and prevents the tappet 2 being forced against the paper 55 strip 1, so that the said strip is not caught between the tappet 2 and the tappet carriage 3 and is prevented from being moved forward into the guide channel 7. A pressure roller 38 is moved in spaced periods 60 of time spring-actingly against the wind-

ing mandrel 8 in the well known manner by means of a cam disc 39, a system of levers 40, and pawl-and-ratchet means 41.

In view of the exchangeability of the winding mandrel and of the plunger, or of the head portions thereof, and by the adjustability of the other operating elements, it becomes possible to manufacture in this manner boxes of different sizes and shape.

The mode of operation of the machine is 75 substantially as follows: The previously folded and gummed or glued neck strip 1 is advanced by means of the tappets or pushing arms 2, 3 and through the cutting device 6 and the rockable guide channel 7, said channel being lowered, in order to make room for other simultaneously operating parts of the machine, as appears from the following description. Upon the release of the winding mandrel 8, that is to say, upon the removal 80 of all interfering operating parts from the path thereof, the guiding channel 7 with the neck strip 1 is oscillated in the direction of the winding mandrel 8 and the end of the strip 1 is clamped by means of the clamping 85 element 19 in such a manner that it becomes disposed substantially upon the middle portion of the lower longitudinal part of the winding mandrel (Fig. 2). The winding mandrel being now rotated (direction of the arrow is Fig. 2), it carries the strip 1 along with it which is simultaneously retained in 90 position by the pressure roller 38. After the completion of the rotation of the mandrel, the frame 14 with the supporting springs 13 is pushed over the strip 1 which latter is 95 now moved onto the plunger section 15 (Fig. 4) by means of the lugs 16 of the supporting springs 13 sliding in the grooves 17. At the same time the main card board pattern 45 which has been retained by the carrying bracket 24 is now released and is dropped in front of the tube member 22. Thereupon 100 the parts 15 and 13 are commonly moved in the direction of the tube member 22 and the 105 plunger 15 pushes the card board pattern 45 into the spring-acting part 23 of the tube 22 and in this movement it causes the folded edge portions of the card board pattern to be bent in contact with the neck strip 1 which has been advanced by the supporting 110 springs 13, the folded marginal portions being thereby secured to the glued parts of the neck strip (Fig. 5). The frame 14 with the supporting springs 13 is then rapidly 115 returned to its initial position, while the plunger section 15 pushes the box thus obtained into the tube 22 so far that the box becomes disposed behind the projecting, spring-acting tube section 23, so that upon 120 the then occurring return movement of the plunger section 15 the box is retained by the projecting walls 23 and remains in the tube 22. Upon the commencement of this stage of 125 operation a fresh card board pattern 45 is 130

also admitted to the supporting arm 24 and consequently the feeler is also operated upon the passage of the particular card board pattern and thereby the tappets 2, 3 are released and by this means the next strip 1 is pushed forward, as already described, through the cutting element 6 and the lowered guide channel 7. After these supporting springs 13, upon their return, have moved past the winding mandrel, the guide channel 7 with the strip is rocked in the direction towards the winding mandrel, as above described, and the strip is thereby caught and is carried along by the now rotated winding mandrel, and so on, as hereinbefore described. Thus, several stages of movement are carried out during the same periods of time, so that no part of the operating time is lost.

20 The finished boxes are given sufficient time to dry upon being pushed through the tube 22 which surrounds them snugly fitting.

It should, of course, be understood that the invention is susceptible of modifications and changes in the different arrangement of the parts and the construction thereof, without deviating from the scope and spirit of the invention as expressed in the appended claims.

30 I claim:

1. The method of making boxes and the like, which consists in gluing a neck strip on one side thereof, bending said strip, bringing said neck strip and a correspondingly bent box pattern into juxtaposition, and simultaneously shaping said box pattern into box form and applying the neck strip thereto.

2. The method of making boxes and the like, which consists in gluing a neck strip to one side thereof, cutting said strip to the required length, feeding a box pattern from a supply, bending the severed neck strip into substantially box-shape, forcing the box-pattern into a mould and thereby bending said box pattern into shape, moving the bent-neck strip into interior contact with the bent box pattern and uniting the strip and the pattern.

3. The method of making boxes and the like, which consists in one-sidedly gluing a neck strip, moving a prepared box pattern at an angle to said strip and simultaneously cutting and advancing said strip, bending said strip on a movable carrier into substantially box-shape with the glued side outwards, gripping the strip against the carrier, placing the box pattern in front of a mould, forcing the carrier with the strip against the box pattern and into the mould with its glued side in adhering contact with the bent sides of the box pattern, and quickly releasing the grip on the neck strip.

4. The method of making paper and card-board boxes and the like, which consists in one-sidedly gluing a neck strip, moving a

prepared box pattern at an angle to said strip and substantially simultaneously advancing said strip and severing off the required length thereof, winding and bending the strip into substantially box shape 70 with the glued side outwards, introducing the box-pattern into molding means, and simultaneously feeding another prepared box pattern and another glued neck strip at an angle to each other into an intermediate not-engaging position, rocking the last mentioned glued bent-neck-strip out of the way of the first mentioned bent neck-strip, moving said bent neck strip towards the first mentioned box-pattern and thereby forcing 80 the first mentioned box pattern and the first mentioned neck strip into the mould and bending them into final box-shape and forcing the glued side of said neck strip into contact with the adjacent walls of the first-mentioned box pattern. 85

5. The method of making paper- and card-board boxes and the like, which consists in one-sidedly gluing a neck-strip at the outside thereof, feeding a prepared box pattern at an angle relatively to said strip and simultaneously severing off the desired length of said strip, retaining said box-pattern and the severed length of strip in an intermediate, not-engaging position, moving 95 said severed strip to the side, moving another previously outwardly glued and bent strip-portion into adhering contact with another previously box-like-bent box pattern, and then bending the previously first-mentioned strip and box pattern into box-shape 100 and feeding them into interior contact with each other.

6. In a device of the kind described, in combination, neck-strip gluing, feeding and cutting means, intermittently rotated winding means for said strip, a connecting passage for the strip, intermediate the cutting means and the winding means, and movable towards and away from said winding means, 105 strip gripping means engageable with the strip and with the winding means, feeding and holding means for a box pattern, and means engageable with the winding means, adapted to project the strip into the path 110 of the box-pattern feeding and holding means.

7. In a device of the kind described in combination, neck-strip gluing, feeding and cutting means, intermittently rotated winding means for said strip, a guiding passage for said strip intermediate the winding means and the cutting means and operatively connected to said cutting means, and periodically rockable, strip gripping means, 120 spring actingly engageable with the strip and with the winding means, feeding, holding and moulding means for a box pattern, and means engageable with the winding means, adapted to project the strip into the 125 path of the box-pattern feeding and holding means.

65 8. In a device of the kind described in combination, neck-strip gluing, feeding and

path of the box-pattern, holding and moulding means.

8. In a device of the kind described in combination, neck-strip gluing, feeding and cutting means, intermittently rotated winding means for said strip, a guiding passage for said strip intermediate the winding and cutting means and movable towards and away from said winding means, feeding, holding and moulding means for a box-pattern, an axially movable head in the axial extension of the winding means and engageable therewith, periodically axially movable holders, surrounding the winding means and the head, and adapted to shift the wound strip from the winding means onto the head, and means to move said head, with the strip into engagement with the box-pattern and the moulding means therefor.
9. In a device of the kind described in combination, neck-strip gluing, feeding and cutting means, intermittently rotated winding means for said strip, a guiding passage for said strip intermediate the winding and cutting means and laterally movable spring-operated gripping means engageable with said winding means, an axially movable, reciprocable head in axial alignment of the winding means and engageable therewith, periodically axially movable spring-fingers engageable with the winding means and with the head, means to periodically reciprocate said fingers, and adapted to shift the strip from the winding means onto said head, feeding holding and moulding means for a box pattern, at an angle to the strip-feeding and strip-winding means, and means to move the head with the strip thereon into the path of the box pattern and into engagement with the box-pattern-holding and moulding means and into engagement with the box-pattern lodged therein.
10. In a device of the kind described in combination, box-pattern feeding means, and neck-strip feeding means, spacedly disposed and substantially at right angle to each other, strip gluing means in front of the strip-feeding means, and strip cutting means at the rear of the strip-feeding means, a feeler operatively associated with the box-pattern-feeding means, and engageable with the strip-feeding means, and adapted to arrest said strip-feeding means in the case of failure to feed of the box-pattern feeding means, moulding and guiding means for the box-pattern, strip-winding means behind the strip-cutting means, and means operatively engageable with the winding means and movable towards the moulding and guiding means for the box pattern and into engagement therewith and adapted to force the wound strip and the box-pattern into said moulding and guiding means.
11. In a device of the kind described in combination, box-pattern feeding means and
- neck-strip feeding means, spacedly disposed and substantially at right angle to each other, strip gluing means on one side of the strip-feeding means, and strip severing means at the other side of the strip feeding means, a pivotally mounted feeler operatively associated with the box-pattern feeding means, an operating bar, linked to said feeler and engageable with said neck-strip feeding means, and adapted to move the same into inoperative position, partially spring-actuated, substantially tube-shaped moulding and guiding means for the box-pattern, and in the path of movement of the box-pattern feeding means, strip winding means behind the strip severing means, and means operatively engageable with said winding means and movable towards the guiding and moulding means for the box pattern and into telescoping engagement therewith and adapted to force the wound strip and the box-pattern into contact with each other and into the guiding and moulding means.
12. In a device of the kind described, in combination, box-pattern feeding means, and neck-strip feeding means spacedly disposed and substantially at right angle thereto, strip winding means, and strip severing means intermediate the strip winding means and the strip feeding means, an intermittently rockable pivoted holding arm, operatively associated with the box-pattern feeding means, a laterally yieldable, substantially box shaped guiding and moulding member for the box pattern underneath said holding arm and in axial alignment with the strip-winding means, a tubular guide-extension at the outer end of said moulding means, and means operatively engageable with said strip-winding means and movable into engagement with the box-shaped guiding and moulding member, and adapted to force the wound strip and the box-pattern into said member and in contact with each other.
13. In a device of the kind described in combination, box-pattern feeding means, and neck-strip feeding means spacedly disposed and substantially at right angles thereto, intermittently movable tappets on said strip-feeding means, a pivotally disposed feeler on said box-pattern-feeding means, tappet-guiding means, an arresting member, linked to said feeler, and adapted to move said tappets into inoperative position in a certain position of the feeler, a stop on said guiding means arrestingly engageable with one of said tappets in said inoperative position, strip-severing means in axial alignment with the strip-feeding means, strip winding means behind the strip-severing means and operatively associated therewith, partially laterally yieldable, substantially tubular box-pattern

- moulding and guiding means below the box-pattern feeding means and in axial alignment with the strip-winding means, and moving means, reciprocably engageable with said winding means and with the strip thereon, and adapted to move said strip into said substantially tubular box-pattern moulding and guiding means and into contact with the box pattern therein.
14. In a device of the kind described in combination, box-pattern feeding means and neck strip feeding means, spacedly disposed at an angle to each other, gluing, and severing means for the strip on said strip-feeding means, a periodically rotated winding man-
- drel behind the strip severing means and adapted for the reception of the severed strip, a substantially tubular box-pattern moulding and guiding means, a laterally yieldable section on said moulding and guiding means, an exchangeable axially reciprocable member housed in said winding mandrel and movable towards and away from said laterally yieldable section, and adapted to transfer the wound strip to said moulding section, and box-pattern feeding means cooperating with said tubular box-pattern moulding and guiding means. 20 25
- In testimony whereof I affix my signature.
- GÜNTHER MEYER-JAGENBERG.
